UNITED STATES PATENT OFFICE.

HATTIE ROSSIE HAYES, OF SALIX, IOWA.

DEVICE FOR PREVENTING HENS FROM SETTING.

1,274,266.

Specification of Letters Patent. Patented July 30, 1918.

Application filed December 29, 1917. Serial No. 309,527.

To all whom it may concern:

Be it known that I, Mrs. HATTIE Rossie HAYES, a citizen of the United States, residing at Salix, in the county of Woodbury and State of Iowa, have invented new and useful Improvements in Devices for Preventing Hens from Setting, of which the following is a specification.

This invention relates to devices adapted to be used for preventing hens from setting and it consists in the novel features hereinafter described and claimed.

It is well known in poultry breeding that during the period of incubation the breast of the fowl becomes unduly heated, producing a desire to remain on the nest, or set as it is technically known. The object, therefore, is to provide means whereby the fowl will be prevented from sitting on the nest in a manner that its breast will be in contact with the nest or eggs therein but which will not interfere with the movement of the hen while roosting or feeding. Thus the fowl does not lose flesh and will soon begin laying and when the desire to set ceases the device may be removed from the fowl and preserved for future use.

In the accompanying drawing:—

Figure 1 is a side view of a hen with the device applied.

Fig. 2 is a perspective view of the device.

The body portion of the device is composed of a single piece of wire which is bent at a point approximately mid-way between its ends to form a loop 1 adapted to pass over the anterior portion of the body of the fowl. From the ends of the loop 1 the wire is carried down and back and twisted forming forward legs 2. From the upper ends 40 of the said legs 2 and at the opposite sides of the device the wire is carried back thereby forming side portions 3 adapted to lie along the opposite sides of the body of the fowl between the body and the legs. From 45 the rear ends of the side portions 3 the wire is extended down and up and twisted forming rear legs 4. From the upper ends of the legs 4 the wire is carried up and over forming a loop 5 by twisting the ends of the 50 wire together as at 6. The loop 5 is adapted to pass over the posterior portion of the body of the fowl. A coil spring 7 is connected at one end with the upper portion of the loop 5 and is provided at its other 55 end with a hook 8 which is adapted to engage under and around the upper intermedi-

ate portion of the loop 1 when the device is applied, and thereby hold the loops at desired positions with relation to each other and the device upon the body of the fowl. 60

To apply the device the hook 8 is disconnected from the loop 1 and the lower end portions of the legs 2 and 4 are squeezed together whereby the upper portions of the loops 1 and 5 are spread abnormally with relation to each other. The loop 1 is then passed over the head, neck and forward portion of the back of the body of the fowl and the loop 5 is carried under the breast and up over the tail and the upper portion of the 70 rear part of the back. The legs 2 and 4 are then released whereby the upper portions of the loops 1 and 5 move toward each other and the said loops will be located one in the front of the wings of the fowl and the other 75 behind the same. The spring 7 is then stretched and the hook 8 is engaged with the upper portion of the loop 1 and the said spring will lie along the spine of the fowl at the median portion of the back. 80

To remove the device the operation above described is reversed. It will be seen that when the device is applied that there are no parts which interfere with the respiration of the fowl, digestion or evacuation and that 85 the wings are free for movement as well as the legs. When the device is applied the depending legs 2 and 4 will prevent the fowl from sitting or squatting and hence it will be impossible to cover the setting of 90 eggs which are in a nest. At the same time the legs 2 and 4 are spaced from each other for a distance sufficient to permit a perch to pass between them and thus when the fowl is roosting the presence of the device does 95 not interfere.

From the foregoing description taken in conjunction with the accompanying drawing, it will be seen that a device of simple structural arrangement is provided which 100 may be easily and quickly applied to the body of a fowl and removed therefrom and when applied the device will effectually prevent the fowl from sitting on a nest with the object and purposes in view as hereinbefore explained. 105

Having described the invention what is claimed is:—

1. A device as described comprising a member provided with a loop adapted to 110 pass over the anterior portion of the body of a fowl, depending legs provided at the

lower portion of said loop, side portions extending rearwardly from said legs, other legs depending from the rear ends of the side portions, and a loop provided at the 5 upper ends of the last mentioned legs and adapted to extend over the posterior portion of the body of the fowl and a spring connected with one of the said loops and detachably connected with the other and 10 adapted to lie along the back of the fowl.

2. A device as described comprising a body portion formed from a single piece of wire and having a forward loop adapted to pass over the anterior portion of the body of

a fowl and being open at its lower side, legs 15 depending from the said loop, side portions extending rearwardly from the said legs, other legs depending from the rear ends of the side portions, a loop provided at the upper ends of the last mentioned legs and 20 adapted to pass over the posterior portion of the body of the fowl and a spring connected with one of the loops and detachably connected with the other and adapted to lie along the back of the fowl.

25

In testimony whereof I affix my signature.

MRS. HATTIE ROSSIE HAYES.
